UNITED STATES PATENT OFFICE

2,433,001

DIPPER TOOTH

George W. Mork, South Milwaukee, Wis., assignor
to Bucyrus-Erie Company, South Milwaukee,
Wis., a corporation of Delaware

Continuation of application Serial No. 513,675,
filed December 10, 1943. This application filed
November 29, 1945, Serial No. 631,603

7 Claims. (Cl. 37—142)

1

My invention relates to new and useful improvements in dipper teeth for excavating dippers, and more particularly to teeth which comprise a base which fits into a socket on the lip of the dipper, and a cap-shaped removable and renewable wearing tip, which tip in turn comprises a relatively hard portion for doing the digging, and a relatively malleable portion for securing the tip to the base.

This is a continuation of my application, Serial No. 513,675, filed December 10, 1943, and since abandoned, for improvements in Dipper teeth.

It is the principal object of my invention to devise a base and tip such as to facilitate a snug and secure fit with the minimum of accurate machining, and such as to be readily attached and removed.

In addition to my principal object, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description the same reference number is applied to the same member or to similar members.

Figure 1 is a plan view of my base from below.

Figure 2 is a side elevation of this same base.

Figure 3 is a vertical section of this same base, taken along the lines 3—3 of Figure 3.

Figure 4 is a side elevation of my point.

Figure 5 is a rear elevation of this same point, taken along the lines 5—5 of Figure 4.

Figure 6 is a section of the two parts of my tooth assembled, taken along the line 6—6 of Figure 7.

Figure 7 is a side elevation of the two parts of my tooth assembled.

Turning now to Figures 1, 2 and 3, we see that the tooth base there portrayed has a flat truncated rectangular pyramidal portion 11 projecting downwardly from its wedge-shaped forward end 12. The slopes of this pyramid could optionally be curved instead of flat. Between this portion 11 and a slight change in slope 13 of the wedge, there is formed a transverse recess 14. However this slight change of slope exists merely to protect the shank, and is not essential to my present invention. What is essential is the rear shoulder of portion 11, which shoulder need not (although it preferably should) extend clear across the tooth.

2

The side slopes of the portion 11 are shown at 15, 15 in Figure 3.

The rear end 16 of my base is shown hexagonal for insertion in a hexagonal hole in the dipper-lip; but, of course, it could be any other shape to register with whatever other shape of hole was used, or it could attach in any other conventional manner.

Turning now to Figures 4 and 5, we see that my tip comprises a rectangular slab 17 of tool steel with beveled ends, and a box-like portion 18 of soft malleable metal welded thereto. When, in the claims, I refer to "upper" and "lower" portions, this is merely for the purpose of correlating the cooperating portions of base and tip, and does not imply what position my tool occupies during digging.

It will be readily seen that the slabs of tool steel can be cut from a sheet or flat bar thereof, 20 with absolutely no wastage, except sawdust.

My base is so forged or cast as to fit snugly, but not tightly, within the box 18 of my tip.

When the tip has been driven firmly onto the base, the rear lower edge 19 of box 18 of the tip 25 is hammered over into recess 14 of the base, as shown in Figures 6 and 7.

I realize that somewhat similar two-part teeth in the past have had one or more rearwardly projecting tongues on the tip, to be hammered 30 into a corresponding recess or corresponding recesses on the base. I have tried this and found that it is not practical, for the reason that the unsupported tongue is not strong enough to hold the tip in place, even if the tongue be widened to 35 extend practically clear across the base. The tongue either breaks off; or, if it does not, it can too easily straighten out and thus loosen the tip from the base.

But, by bending a portion of the continuous 40 rear edge of the box 18 into the recess on the base, I have found that the two corner edges of this box constitute two "beams" to support the bent portion of the rear edge, and furthermore that the sinuous conformation of the bend (which 45 would not exist with a simple tongue, no matter how wide) renders unbending enough more difficult than would be the unbending of a tongue, so that my tooth does not tend to work loose. Still furthermore, due to the rigidity of the two 50 "beams," the bending of the rear edge of the box into place, stretches this rear edge; and hence unbending would require compression of the bent portion. This enhances the difficulty of unbending, already alluded to.

Nevertheless the tip can be removed by hammering against bevel 20.

Having now described and illustrated one form of my invention, I wish it to be understood that my invention is not to be limited to the specific form or arrangement of parts herein described and shown.

I claim:

1. In a two-piece dipper tooth, the combination of a wedge-shaped base and a cooperating cap-shaped tip, the former having a rearward-facing shoulder on the lower face of the wedge, and the latter comprising an upper hard digging portion and a lower malleable portion, which malleable portion comprises a bottom section and two side sections, the bottom section and at least the adjacent part of the side sections extending beyond the outer edge of the shoulder, and this extending part of the bottom section being capable of being bent over the shoulder to secure the two pieces removably together, whereupon the junctures between the bottom section and the two side sections serve to brace the thus bent part of the bottom section.

2. In a two-piece dipper tooth, the combination of a wedge-shaped base and a cooperating cap-shaped tip, the former having at least one rearward-facing shoulder, and the latter comprising an upper hard digging portion and a lower malleable portion, which malleable portion comprises a bottom section and two side sections, the bottom section and at least the adjacent part of the side sections extending beyond the outer edge of the shoulder, and this extending part of the bottom section being capable of being bent over the shoulder to secure the two pieces removably together, whereupon the junctures between the bottom section and the two side sections serve to brace the thus bent part of the bottom section.

3. A dipper-tooth according to claim 2, further characterized by the fact that the front lower

portion of the wedge-shaped base is a flat truncated rectangular pyramid, the rear slope of which forms the shoulder.

4. A dipper-tooth according to claim 2, further characterized by the fact that the front lower portion of the wedge-shaped base is a flat truncated rectangular pyramid, and that the lower face of the wedge just beyond this pyramid has an increased slope, thus forming a recess between the pyramid and this slope.

5. A dipper-tooth according to claim 1, characterized by the fact that the shoulder extends transversely clear across the base.

6. A dipper-tooth according to claim 2, characterized by the fact that the shoulder extends transversely clear across the base, and that the lower edges of the base ahead of this shoulder are sloped.

7. A dipper-tooth according to claim 2, characterized by the fact that the rear edge of the upper hard digging portion projects above the surface of the base, whereby the sealing contact of the rear edge of the malleable portion with the base can be broken by hammering on the rear edge of the hard digging portion.

GEORGE W. MORK.
